UNITED STATES PATENT OFFICE.

INA H. E. VOGLE, OF SAN FRANCISCO, CALIFORNIA.

DESIGN FOR A SEWING-ARTICLE-SUPPORTING DOLL.

Application filed December 29, 1925. Serial No. 15,894. Term of patent 7 years.

To all whom it may concern:

Be it known that I, INA H. E. VOGLE, a citizen of the United States of America, residing at San Francisco, county of San Francisco, and State of California, have invented a new, original, and ornamental Design for a Sewing-Article-Supporting Doll, of which the following is a specification, reference being had to the accompanying drawing, forming part thereof.

The figure is a perspective view of the doll, showing my new design.

I claim:

The ornamental design for a sewing article supporting doll, as shown.

INA H. E. VOGLE.
